UNITED STATES PATENT OFFICE

148,580

DESIGN FOR A CUP OR SIMILAR ARTICLE

Violet Ross, Hawthorne, Calif.

Application December 20, 1946, Serial No. 135,643

Term of patent 7 years

(Cl. D44—9)

To all whom it may concern:

Be it known that I, Violet Ross, a citizen of the United States of America and a resident of the city of Hawthorne, in the county of Los Angeles and State of California, have invented a new, original, and ornamental Design for Cup or Similar Article of which the following is a specification, reference being had to the accompanying drawing, forming part thereof.

In the drawing:

Figure 1 is a side elevational view of a cup or similar article, showing my new design,

Figure 3 is a side elevational view of the other side of the cup with a section cut away along the lines 3—3 of Fig. 5,

I claim:

The ornamental design for a cup or similar article, substantially as shown and described.

VIOLET ROSS.
